UNITED STATES PATENT OFFICE

2,018,898

GOLF CLUB

William F. Reach, Springfield, Mass., assignor to
 A. G. Spalding & Bros., New York, N. Y., a
 corporation of New Jersey

Application April 21, 1932, Serial No. 606,719

2 Claims. (Cl. 273—80)

The invention relates to that type of golf club in which provision is made for torsional resiliency at a point between the head and the main body of a tubular metallic shaft. 5 In carrying out the invention the means by which torsional resiliency is obtained comprises a sleeve or tubular member formed separate from the head and its extension or hosel, and from the hollow metal shaft, and forming a connection 10 between said parts.

The head and its extension or hosel may be made of the grade of metal usually employed in said parts, whereas the separately formed torsion member may be of a different grade of metal and 15 tempered to such a degree as will serve the purpose of securing the desired resiliency.

The invention may be carried out in various forms, examples of which are disclosed in the accompanying drawings in which

20 Figure 1 is a sectional view in part of the extension or hosel of a golf club with the improvement in one form embodied therein.

Fig. 2 is a transverse section on line 2—2 of Fig. 1.

25 Fig. 3 is a transverse section on line 3—3 of Fig. 1.

Fig. 4 is a view similar to Fig. 1 of a modified form of assembly with a readily detachable shaft.

Fig. 5 is a view of a further modification, the 30 shaft being shown in section.

Fig. 6 is a view of a modified form of Fig. 5.

Referring to Fig. 1 the head of the golf club is shown at 6. This has an integral extension 7, which in this assembly is in tubular form, substantially like the ordinary hosel. At the bottom of the hosel socket the extension is provided with a screw threaded seat or socket portion 8 to receive the screw threaded lower end of a metallic torsion sleeve 9, which has attached thereto at its upper end by a rivet or cross pin 10 a hollow metallic shaft 11 of substantially ordinary form and dimensions. The torsion sleeve 9 has a formation intermediate of its length to provide for torsional resiliency, and in the particular form shown, this torsional section of the sleeve is formed with lengthwise extending slots 12 in sufficient number to provide torsional resiliency between the head and the shaft when the ball is struck by the head of the club. This 50 torsion sleeve is enclosed substantially by the wall of the hosel. It is slightly spaced therefrom, the clearance between this sleeve and the wall of the hosel being indicated at 13. This clearance extends from the screw threaded connection at 55 the lower end of the torsion sleeve throughout

the major portion of the hosel. At the upper end of the hosel there is provided a recess 14 formed by thinning the wall of the hosel on its interior, and in this recess a rubber tubular member 15 is located to provide resilient contact with the upper end of the torsion sleeve. This rubber member rests upon the shoulder 14 at the bottom of the recess, and it projects inwardly slightly beyond the inner face of the wall of the hosel, so as to afford a yielding bearing for the 10 torsion sleeve at the upper portion thereof.

The shaft extends below the rivet 10 down to about the dotted line 16, and this extension of the shaft is free from any connection with the torsion sleeve, so that relative movement circumferentially can take place between the main body portion of the torsion sleeve and this extension of the shaft. In other words, torsional yielding of the sleeve can take place throughout the major portion thereof below the rivet 10 and 20 above the screw thread connection at 8, and this torsional resiliency can take place circumferentially in relation to the lower end of the shaft, which, as above indicated, lies within the torsional sleeve, and covers the slots therein. 25

This torsional sleeve can be made of highly tempered metal to get the desired resiliency, whereas the hosel may be formed of the usual character of metal. The torsion sleeve is made of thicker metal than the shaft. Should break- 30 age occur in the shaft or in the torsion sleeve, these parts can be removed and replaced with a new part or parts, and the head with its hosel will serve with the new assembly.

Referring to Fig. 4 this shows a torsion sleeve 35 9a within the hosel, and fixed at its lower end by a rivet or cross pin 8a. The hosel has a downwardly tapered bore, and the torsion sleeve is formed to correspond. The upper end of the torsion sleeve is screw threaded on its interior 40 at 10a to receive the screw threaded lower end of the shaft indicated at 11a. In this assembly, should the shaft break, it may be unscrewed from the torsion sleeve and a new one inserted 45 in its place. In this assembly also the torsion sleeve has clearance between itself and the wall of the hosel and there is a rubber cushion member, like in the form first described at 15a.

In the form shown in Fig. 5 the extension of 50 the head consists of a non-tubular or solid member 7x having a reduced portion at 17 which provides a shoulder at 18. This reduced extension 17 receives the torsion sleeve 9x on its exterior, the said tubular torsion member having its lower 55

end abutting against the shoulder 18. A rivet 19 is employed to fasten the lower portion of the torsion sleeve to the reduced extension 17. The hollow metal shaft indicated at 11x is adapted to fit down over the exterior of the torsion sleeve. It is secured to said sleeve near the upper end of the latter by a rivet 10x. The lower edge of the shaft rests upon the shoulder 18. This torsion member 9x is slotted longitudinally at its intermediate portion, thus leaving its intact end portions for connection to the extension or shank of the head, and the tubular shaft respectively.

In this form also the tubular torsion member is made separate from the head, and its extension or shank, and can be of a different grade of metal, and tempered for the purpose of securing the desired resiliency.

Reverting to Fig. 4, instead of fastening the torsion member within the hosel by means of the rivet, this member may be attached by means of a screw thread connection, such as is shown in Fig. 1, and like in Fig. 4 the said torsion sleeve may have a screw thread connection at its upper end with the shaft, so that both the shaft and the torsion sleeve are detachable from the hosel, and also are detachable from each other.

In Fig. 6 the torsion tube 9b like in Fig. 5 extends above the shank or hosel of the head coaxially therewith. Only its lower end is fitted to the said shank which in this case is in the form of a hollow hosel 7b, with the said lower end of the slotted tube lying within it and fixed thereto by a rivet 8b.

The hollow shaft 11b is outside of the slotted tube and is fixed thereto at the upper part thereof by a rivet 10b. The lower edge of this shaft like in Fig. 5 finds a bearing against a part of the extension. In the present instance the shaft abuts the upper edge of the hosel, whereas in Fig. 5, the shaft abuts the shoulder 18 where the shank is reduced.

The hosel socket is tapered downwardly and

the torsion sleeve or tube is formed to correspond.

Certain features may be employed interchangeably in the several forms. For instance, in the present form the rivet holding the slotted tube within the hosel may be replaced by a screw threaded connection like in Fig. 1 to make the slotted tube removable, and this is true of the slotted tube of Fig. 5.

I claim:

1. A golf club comprising a head having a hollow hosel, a tubular metallic shaft, and a tubular metallic torsion absorbing sleeve having its central portion weakened, but having intact end portions, said sleeve lying within said hollow hosel 15 with one end portion attached to the hosel and its other end portion rotatably engaged by the hosel wall, the lower end portion of the shaft lying within the sleeve and extending across the weakened portion thereof, the shaft being attached to the end of the sleeve rotatably engaged by the hosel and rotatably engaging the end of the sleeve attached to the hosel.

2. In a golf club a head having an extension for connection with the shaft, a tubular metallic 25 torsion absorbing sleeve arranged coaxially with said head extension, and with said head extension and sleeve arranged at least partly one with-in the other, a tubular metallic shaft, said shaft and sleeve lying with one at least partially within 30 and embracing the other, means for connecting the lower end portion of the shaft with the upper part of the sleeve, and means for connecting the sleeve at its lower portion with the head extension, the portion of the metallic torsion sleeve 35 between its points of connection with the shaft and head extension being weakened to give the torsion effect, said metallic torsion sleeve being of different grade of metal tempered to a different degree and of thicker wall than the tubular 40 metallic shaft.

WILLIAM F. REACH.
